UNITED STATES PATENT OFFICE.

WILLIAM M. HORTON, OF CLEVELAND, OHIO, ASSIGNOR TO THE ADAMS-BAGNALL ELECTRIC COMPANY, OF CLEVELAND, OHIO, A CORPORATION OF OHIO.

AUTOMOBILE-HEADLIGHT.

1,321,445.

Specification of Letters Patent. Patented Nov. 11, 1919.

Application filed January 4, 1917. Serial No. 140,487.

To all whom it may concern:

Be it known that I, WILLIAM M. HORTON, a citizen of the United States, residing at Cleveland, in the county of Cuyahoga and 5 State of Ohio, have invented certain new and useful Improvements in Automobile-Headlights, of which the following is a specification.

This invention relates to headlights, a 10 pair of automobile headlights being shown herein, it more particularly relating to shiftable reflectors which when shifted in one direction will prevent the glare of the headlight, and when shifted in other directions, increased efficiency of the headlight obtained, one of the objects of the invention being to provide improved means for supporting the reflector in its casing whereby the reflector may have a universal movement 15 in its casing, and which means is very simple in construction and operation and inexpensive to manufacture.

Another object of the invention is the provision in connection with a universally supported reflector of electrically operative means for shifting the reflector.

Another object of the invention is the provision of means for connecting a pair of universally supported reflectors for simultaneous shiftable movement.

In the drawings accompanying and forming part of this specification, Figure 1 is a horizontal sectional view of a pair of conventional headlights, such as those usually 35 used for automobiles with the reflectors thereof connected for simultaneous movement in different directions; Fig. 2 is a front view of the structure shown in Fig. 3; Fig. 3 is an enlarged sectional view of the 40 electric operating means or motor for shifting the reflectors, this view being taken on line 3—3 of Fig. 2, and looking in the direction of the arrows in said figure; and Fig. 4 is a detailed sectional view illustrating the 45 pivotally mounted slotted tubes.

Similar characters of reference indicate corresponding parts in the several figures of the drawings.

The present construction is an improvement in part upon my contemporaneously pending application, Serial No. 135,321 filed December 6th 1916. In that case the reflector was so supported that an up and down movement or a sidewise movement or

a combination of the two within certain 55 limits could be obtained. In the present improvement however, the slotted supporting tubes instead of being rigidly carried by the casing, are pivotally carried thereby with the result that a greater movement of the 60 reflector in any direction is obtained, so that in view of the compound pivoting of the reflector a universal movement thereof is the result.

In the present improvement, each headlight comprises a casing 2 of any suitable design or shape, having a lens 3 attachable thereto in any desired manner. Each casing is provided with a reflector of some suitable form,—in the present instance the reflector of the right hand lamp in Fig. 1 is designated as 4, and the left hand reflector as 4';—each reflector carries the usual bulb or light 5 connected with the source of electrical energy in the usual manner, whereby the light is movable with the reflector. Each reflector is provided with a pair of oppositely located pivot pins 6, each loosely supported by a pivot ball 7, each of which balls is movably carried in a slotted member or tube 8, pivotally secured as at 40 to the inside wall of the casing. This compound pivot construction permits the reflector to swing up or down on its pivot pins relatively to the balls, which support such pins and also permits the reflectors to be swung in a direction transverse to its up and down movement due to the movement of the pivot pins and balls within the slotted tubes, and also permits the reflectors to be swung by a combination of these two movements in such a way that the light may be thrown into different angular positions, so that when the reflector is thrown down the glare of the lamp will be entirely prevented, while when thrown sidewise, a better view of the road is obtained, especially when going around corners or curves, while when these two movements are combined sign posts can be read, thus insuring greater efficiency in the use of the headlights. For swinging the reflectors up and down, or to return them to their horizontal position, one of the reflectors, as 4, is connected by a rod 9 through the medium of a universal connection 10, as by a ball and socket with an eccentric 11, mounted on a shaft 12, on which is secured a ratchet wheel 13 adapted to be engaged by

a pawl 1½ pivotally carried by a pair of arms 15 secured to the shaft 12. The opposite end of this pawl projects as at 16 into a slot 17 of a core or plunger 18, whereby on the 5 movement of the core back and forth the pawl will be operated to rotate the ratchet wheel, it being maintained in operative engagement with such ratchet wheel by a spring 19 secured to a bracket 20 fastened to 10 the rear of the casing 2. This bracket supports the several parts of the motor mechanism 30. The spring 19 is in position to always return the core or plunger 18 to its forward position when it has been drawn 15 rearward or backward by the magnet 21, which is carried by the bracket adjacent to the core or plunger. The ratchet wheel is maintained against slipping backward by a suitable spring pawl 19', also carried by the 20 bracket 20. The core 18 has a contact member 22 at its forward end in position to make contact with a similar contact member 23 carried by a spring member 24 supported on a rigidly upstanding member 25 insulated 25 from the bracket 20. The spring 19 is in position to always return the core or plunger 17 to its forward position to make contact with the armature or spring contact member 24 after such core 18 has been drawn to the 30 rear or backward by the magnet. In other words, the spring 19 acts through the pawl 1½ to return the core or plunger into position to make contact after such contact is broken by the electro-magnet means, so that 35 when the mechanism is put in operation there is a continuous make and break between the contact portions of the core 17 and the member 24, to thus rotate the ratchet wheel 18 and thereby through the eccentric 40 11 shift the reflector, with which it is connected, upwardly or downwardly to the desired extent, the reflector at this time swinging on its pivot pins relatively to the balls. It will of course be understood that the necessary 45 insulations and electrical connections not necessary to describe herein are provided to insure the proper operation of the electro-magnet or motor. A further detail description of this motor and the electrical connections is deemed unnecessary herein as the same is described in my contemporaneously pending application filed December 2, 1916, Serial No. 124,625. The two reflectors are connected by a connecting rod 26 shown as 50 comprising a pair of rods coupled together by a coupling 27, each member of the pair being pivotally connected with an ear or lug 28 secured to the reflector. The rod 26 extends through enlarged or slotted openings 55 29 of the lamp casings, so that when the reflector 4 is shifted up or down the companion reflector 4' will move therewith. A similar motor 30' is placed in the present instance in the lamp casing carrying the 60 reflector 4', but set at right angles to the 65

setting of the motor just described, and an eccentric 31 which is similar to the eccentric 11 hereinbefore referred to, is therefore located at right angles to the eccentric 11, it being likewise suitably connected by links 70 32 with the connecting rod 26 connecting the two reflectors, or a sleeve 26' thereof, whereby on the operation of the motor 30' in a similar manner to the motor 30 hereinbefore described, the reflector 4' will be shifted at 75 right angles to its up and down movement due to the shifting of the balls in the tubular members or raceways, one in one direction and the other in the opposite direction, that is, one forwardly and the other rearwardly, 80 and consequently through the connecting rod 26 the companion reflector 4 will also be shifted in a similar manner. To insure the proper parallel movement of the reflectors, they are also connected by a connecting rod 85 33, comprising a pair of members coupled together by a coupling member 34, one of the rod members as 35 being linked by a pair of links 36 to one of the reflectors shown herein as the reflector 4. This rod 33 extends through enlarged openings or slots 37 in the two casings. The linkage connection 36 provides the proper flexible connection between the two reflectors to permit proper movement thereof when shifted, while the 90 universal connection or some similar flexible connection 10 provides the necessary connection to permit movement of the reflectors by the motor 30' in a manner which will be readily understood. Each motor will be 100 controlled by a proper switch and when the switch of the motor 30 is operated, both reflectors will be swung up or down from their horizontal position in the manner desired and when the switch of the motor 30' is 105 operated, both reflectors will be swung sidewise or transversely of their up and down movement. Obviously by operating both switches simultaneously, the reflector may be shifted into any desired angular position 110 relatively to the casing by reason of the compound pivoting of the reflector on the casing, so that not only an up and down movement and a sidewise movement of the reflector may be obtained, but also a universal 115 movement thereof, since the reflector is not only shiftable by reason of its pivot 6, up and down and sidewise by reason of the ball pivot 7, but by pivoting the slotted tubes on the casing these can also swing so that, as 120 stated, a universal movement of the reflector is made possible, since each compound pivot for each reflector comprises a pair of rotary pivot members connected by a movable pivot member or ball. In other words, the pivot 125 pins 6 rotate with relation to the balls, while the pivotal connections 40 enable the slotted tubes to rotate with relation to the casing, and these two rotary pivotal connections are in turn coupled together by the shiftable 130

balls 7, which move lengthwise of the slotted tubes.

It will be understood that the various details may be more or less changed without departing from the spirit or scope of the present improvement.

Like my companion case hereinbefore last referred to, the pawls may be operated mechanically instead of electrically if preferred.

It will of course be understood that the slotted tubes maintain the balls in proper position, the slots of the tubes being of suitable width to receive the pins 6 and prevent the improper displacement of the balls.

It will be observed that in the present improvement the reflector is itself directly connected with the casing, thus doing away with all intermediate connections, such as annular members, etc., by compound pivotal means, thus materially simplifying the mechanism and reducing the expense of manufacturing the same. It will also be understood of course that the switches for controlling the motors can be located in any desired place, as on the steering wheel or dash board of the vehicle. In practice, of course, the connecting rods between the two reflectors may be located closer together and in fact may run through a suitable tube, if desired.

I claim as my invention:

1. The combination of a lamp casing, a shiftable reflector therein, a pair of pivotal means for connecting the reflector with the casing, each pivotal means comprising a pair of rotatable pivot devices and a member bodily movable relatively to one of said pivot devices for connecting said pivot devices, and means for shifting the reflector.

2. The combination of a lamp casing, a shiftable reflector therein, pivotal means for connecting the reflector with the casing each comprising a pair of rotary pivotal means and ball pivotal means connecting the same, and means for shifting the reflector.

3. The combination of a lamp casing, a shiftable reflector therein, compound pivotal means for directly connecting the reflector with the casing and comprising a pair of pivot pins, a pair of balls for the reception of said pins and a pair of slotted members pivotally connected to the casing, and means for shifting said reflector.

4. The combination of a lamp casing, a shiftable reflector therein, compound pivotal means for directly connecting the reflector with the casing and comprising a pair of pivot pins, a pair of balls for the reception of said pins and a pair of slotted members pivotally connected to the casing, and electrical means for shifting said reflector.

5. The combination of a lamp casing, a shiftable reflector therein, a pair of pivotal means for connecting the reflector with the

casing, each comprising a pair of rotatable pivot devices, a member bodily movable relatively to one of said pivot devices for connecting said pivot devices and in which bodily movable member the other pivot device is rotatable, and electrical means for shifting the reflector.

6. The combination of a lamp casing, a shiftable reflector therein, pivotal means for connecting the reflector with the casing each comprising a pair of rotary pivotal means and ball pivotal means connecting the same, and electrical means for shifting the reflector.

7. The combination of a lamp casing, a shiftable reflector therein, compound pivotal means for directly connecting the reflector with the casing and comprising a three-part pivotal structure, and means for shifting said reflector.

8. The combination of a lamp casing, a shiftable reflector therein, compound pivotal means for directly connecting the reflector with the casing and comprising a three-part pivotal structure, and electrical means for shifting said reflector.

9. The combination of a lamp casing, a shiftable reflector therein, a pair of compound pivotal means for supporting the reflector relatively to the casing for universal movement, each compound pivotal means comprising a pair of pivot members and means connecting said pivot members whereby the reflector is supported for universal movement relatively to its casing, and means for shifting the reflector.

10. The combination of a lamp casing, a shiftable reflector therein, a pair of compound pivotal means for supporting the reflector relatively to the casing for universal movement, each compound pivotal means comprising a pair of pivot members and means connecting said pivot members, said connecting means being supported by one of said pivot members and in turn supporting the other pivot member, and electrical means for shifting the reflector.

11. The combination of a lamp casing, a shiftable reflector therein, means for supporting the reflector directly on the casing for universal movement, and electrical means located directly between the rear wall of the shiftable reflector and the casing for shifting the reflector.

12. The combination of a lamp casing, a shiftable reflector therein, means for supporting the reflector and comprising a pair of oppositely located pivot pins secured to the reflector, a pair of balls in which the pivot pins rotate, slotted members pivotally secured to the casing for receiving said balls, and means for shifting the reflector.

13. The combination of a lamp casing, a shiftable reflector therein, means for supporting the reflector and comprising a pair

of oppositely located pivot pins secured to the reflector, a pair of balls in which the pivot pins rotate, slotted members pivotally secured to the casing for receiving said balls, 5 and electrical means for shifting the reflector.

14. The combination of a lamp casing, a shiftable reflector therein, means for supporting the reflector and comprising a pair 10 of oppositely located pivot pins secured to the reflector, a pair of balls in which the pivot pins rotate, slotted members pivotally carried by the casing for receiving said balls, and means for shifting the reflector and 15 comprising a make and break electrically operative means carried by the casing.

15. The combination of a lamp casing, a shiftable reflector therein, means for supporting the reflector for universal movement, means for shifting the reflector up or 20 down, means for shifting the reflector sideways, the organization being such that the reflector may be shifted by a combination of these movements into various angular positions, each of said shifting means including 25 electrically operative means.

16. The combination of a lamp casing, a shiftable reflector therein, means for supporting the reflector for universal movement, and electrically operative means located directly between the rear wall of the 30 shiftable reflector and the casing for shifting the reflector.

17. The combination of a pair of headlight casings, a pair of reflectors, a three-part compound pivotal means for supporting each of the reflectors, electrical means for operating the reflectors in one direction, and an independent electrical means for operating the reflectors in another direction. 35

18. The combination of a pair of headlight casings, a pair of reflectors, a three-part compound pivotal means for supporting each of the reflectors, electrical means for operating the reflectors in one direction, and an independent electrical means for operating the reflectors in another direction, each of said electrical means comprising an electric motor. 45

50 19. The combination of a pair of headlight casings, a pair of reflectors, a three-part compound pivotal means for supporting each of the reflectors, electrical means for operating the reflectors in one direction and an independent electrical means for operating the reflectors in another direction, each of said electrical means comprising an electric motor, one located in each casing and set at right angles to the other. 55

60 20. The combination of a pair of lamp casings, a shiftable reflector in each of said casings, means for supporting each of said reflectors for universal movement, means connecting the reflectors for simultaneous movement, and means for shifting the reflectors 65

in different directions and including a make and break electrically operative means.

21. The combination of a pair of lamp casings, a shiftable reflector in each of said casings, means for supporting each of said reflectors for universal movement, means connecting the reflectors for simultaneous movement, and means for shifting the reflectors in different directions and including a make and break electrically operative means 70 comprising a pair of motors. 75

22. The combination of a pair of lamp casings, a shiftable reflector in each of said casings, means for supporting each of said reflectors for universal movement, means connecting the reflectors for simultaneous movement, and means for shifting the reflectors in different directions and including a make and break electrically operative means 80 comprising a pair of motors, one located in each casing. 85

23. The combination of a pair of lamp casings, a shiftable reflector in each of said casings, means for supporting each of said reflectors for universal movement, means connecting the reflectors for simultaneous movement, and means for shifting the reflectors in different directions and including a make and break electrically operative means 90 comprising a pair of motors, one located in each casing and one operative to shift the reflectors in certain directions and the other operative to shift the reflectors in different directions and located one at right angles to the other. 95

24. The combination of a pair of lamp casings, a shiftable reflector in each of said casings, means for supporting each of said reflectors for universal movement, means connecting the reflectors for simultaneous movement, and means for shifting the reflectors in different directions and including a make and break electrically operative means and comprising a pair of motors, one located in each casing and one operative to shift the reflectors in certain directions and the other operative to shift the reflectors in different directions and located one at right angles to the other and said motors being a duplicate one of the other, each comprising 100 an electro-magnet, a shiftable core, a pawl connected with the core, a ratchet wheel operated by the pawl, a spring for controlling the movement of the pawl in one direction, and means connecting the reflectors with the ratchet wheels. 110 115

25. The combination of a pair of lamp casings, a reflector in each of said casings, means connecting the reflectors for simultaneous movement, a three-part compound pivotal means for pivotally supporting each reflector within its casing, and a pair of duplicate electrically operating means for shifting the reflectors. 120

26. The combination of a pair of lamp 125

casings, a reflector in each of said casings, means connecting the reflectors for simultaneous movement, compound pivotal means for pivotally supporting each reflector within its casing and comprising a pair of pivots, a pair of pivotal balls and a pair of pivoted slotted members, and duplicate means for operating the reflectors.

27. The combination of a pair of lamp casings, a reflector in each of said casings, means connecting the reflectors for simultaneous movement, compound pivotal means for pivotally supporting each reflector within its casing and comprising a pair of pivots, a pair of pivotal balls and a pair of pivoted slotted members, and duplicate means for operating the reflectors, one organized for operating the reflectors in certain directions and the other in different directions.

28. The combination of a pair of lamp casings, a reflector in each of said casings, means connecting the reflectors for simultaneous movement, compound pivotal means for pivotally supporting each reflector within its casing and comprising a pair of pivots, a pair of pivotal balls and a pair of pivoted slotted members, and duplicate electrically operating means for operating the reflectors.

29. The combination of a pair of lamp casings, a reflector supported in each of said casings for universal movement, a pair of means each connecting the reflectors for simultaneous movement and insuring a parallel movement thereof, and means for shifting the reflectors.

30. The combination of a pair of lamp casings, a reflector supported in each of said casings for universal movement, a pair of means each connecting the reflectors for simultaneous movement and insuring a

parallel movement thereof, and electrical means for shifting the reflectors.

31. The combination of a lamp casing, a shiftable reflector therein, a pair of pivots carried by the reflector, a pair of bodily movable members carrying said pivots, a pair of pivotally supported guide-ways for said bodily movable members, and means for shifting said reflector.

32. The combination of a lamp casing, a shiftable reflector therein, a pair of pivots carried by the reflector, a pair of bodily movable members carrying said pivots, a pair of pivotally supported guide-ways for said bodily movable members, and electrical means for shifting said reflector.

33. The combination of a pair of lamp casings, a shiftable reflector in each of said casings, pivotal means for connecting each reflector with its casing and comprising a pair of pivots, a pair of bodily movable members carrying said pivots and a pair of pivotally supported guide-ways for said bodily movable members, means for connecting the reflectors for simultaneous movement, and means for shifting said reflectors together.

34. The combination of a pair of lamp casings, a shiftable reflector in each of said casings, pivotal means for connecting each reflector with its casing and comprising a pair of pivots, a pair of bodily movable members carrying said pivots and a pair of pivotally supported guideways for said bodily movable members, means for connecting the reflectors for simultaneous movement, and electrical means for shifting said reflectors together.

Signed at Cleveland, Ohio, this 2nd day of Jan., 1917.

WILLIAM M. HORTON.
